United States Patent Office.

JOHN H. DOERR, OF PHILADELPHIA, PENNSYLVANIA.

Letters Patent No. 99,298, dated February 1, 1870.

IMPROVED CHAIN OR BAND.

The Schedule referred to in these Letters Patent and making part of the same.

To all whom it may concern:

Be it known that I, JOHN H. DOERR, of Philadelphia, county of Philadelphia, State of Pennsylvania, have invented a new and useful Improvement on Springs, Chains, and Endless Bands; and I do hereby declare that the following is a full, clear, and exact description of the construction and operation of the same, reference being had to the annexed drawings, making a part of this specification, in which—

Figure 1 represents a side view of the chain, showing the links loosely connected.

Figure 2 represents the inner side of the chain.

Figure 3, the top side of the same.

Figures 4 and 5 show the position of two single links to each other, for the purpose of joining them.

Figure 6 is a side view of the spring.

Similar letters of reference indicate corresponding parts in the several figures.

The object of my invention is to construct springs, chains, and endless bands from a suitable number of sections or links, in such a manner that all the sections or links composing the said springs, chains, or bands, can be easily put together and detached from each other.

My improved springs I propose to use as a motive-power for driving machinery, lifting weights, &c.

My improved chains and endless bands I propose to use for the purpose of transmitting power, and in many cases where common chains, common iron bands, or wire ropes are now employed, as, for instance, in the construction of suspension-bridges.

To enable others skilled in the art to make and use my invention, I will proceed to describe its construction and operation.

My improved spring, chain, or band consists of a suitable number of sections or links, made of steel, band-iron, or other suitable material.

Each section or link is provided with a crescent-shaped head or hook, *z*, which is slightly bent, and with a triangular slot or eye, *s*, in the middle, as shown in figs. 4 and 5.

In order to connect these sections, I have to hook

or attach one section to the other, by means of the head *z* and the slot *s*, and to proceed in this way till all the sections which compose my improved spring, chain, or band are in their regular position, as shown in figs. 2 and 3.

In the construction of my improved chains or endless bands, I use sections of uniform length, which ought to be only long enough to overlap each other so far as to cover the slots *s*; but in the construction of my improved spiral springs, I use sections of different, gradually-increasing length. The shortest section I place in the centre of the spiral, the next in length is hooked to the first, and so forth, each following overlapping the preceding, till all are attached to each other, as shown in fig. 6.

In this way, one section serving as support to the other, I multiply the thickness and increase the strength of my improved springs, chains, and bands, and besides this, I gain the advantage that if a breakage should occur, it will be sufficient to detach and take out the broken section and replace it by a sound one. The whole will then be as perfect as before, and need not to be thrown away.

To springs constructed in sections, after my plan, can evidently be given a more uniform temper and a greater strength than to common springs, and chains manufactured in the above-described manner will be stronger, because their links can be cut out of band-iron or steel, without any welding or riveting, which weakens ordinary chains.

What I claim as my invention, and desire to secure by Letters Patent, is—

The construction of springs, chains, or endless bands of a number of detachable sections or links, each provided with the peculiarly-formed head or hook *z*, and the slot or eye *s*, contiguous to said head, in the manner and for the purposes substantially as set forth.

JOHN H. DOERR.
